AXLE SUPPORTED TOILET TISSUE ROLL DISPENSING CONTAINER

David Goldberg, Brooklyn, N. Y.

Application May 19, 1954, Serial No. 30,564

Term of patent 14 years

(Cl. D4—3)

I claim:

The ornamental design for an axle supported toilet tissue roll dispensing container, as shown.
